United States Patent

Des. 240,029
Patented May 25, 1976

240,029

BOAT

William I. B. Crealock, 1401 Forest Ave.,
Carlsbad, Calif. 92008

Filed Sept. 5, 1974, Ser. No. 503,505

Term of patent 14 years

Int. Cl. D12—06

U.S. Cl. D12—64

FIG. 6

FIG. 7

FIG. 8

FIG. 9

FIG. 10

FIG. 1 is a perspective view looking from the aft starboard side of the boat.

FIG. 2 is a top plan view of the boat.

FIG. 3 is a side elevational view of the starboard side of the boat. The port side is substantially identical in appearance to the starboard side.

FIG. 4 is an elevational view from the stern.

FIG. 5 is an elevational view from the bow.

FIGS. 6, 7, 8 and 9 are profile elevational views taken along sections 6, 7, 8 and 9 of FIG. 3.

FIG. 10 is a conventional half-section view showing the hull profile of stations 0-10 at a location corresponding to stations 0-10 of FIG. 3.

The partial disclosure of surface texture is representative of the complete appearance within the borders shown.

What is claimed is:

The ornamental design for a boat, substantially as shown and described.
